UNITED STATES PATENT OFFICE.

WILLIAM BENDER, JR., OF SOUTH BEND, INDIANA.

DESIGN FOR A RADIOCABINET.

Application filed October 23, 1926. Serial No. 19,455. Term of patent 3½ years.

To all whom it may concern:

Be it known that I, WILLIAM BENDER Jr., a citizen of the United States, residing at South Bend, in the county of St. Joseph and State of Indiana, have invented a new, original, and ornamental Design for Radiocabinets, of which the following is a specification, reference being had to the accompanying drawing, forming part thereof.

Figure 1 is a perspective view of a radio cabinet, with its front drop panel open, showing my new design.

Figure 2 is a perspective view of the cabinet showing its front drop panel in closed position.

Figure 3 is a top or plan view of the cabinet.

I claim:

The ornamental design for a radiocabinet as shown.

WILLIAM BENDER JR.
